Greenseller

ATTORNEYS.

UNITED STATES PATENT OFFICE.

JOHN C. WHITMORE, OF PETERSBURG, VIRGINIA.

SLAB SHINGLE.

Application filed February 16, 1923. Serial No. 619,382.

To all whom it may concern:

Be it known that I, JOHN C. WHITMORE, a citizen of the United States, and a resident of Petersburg, in the county of Dinwiddie and State of Virginia, have invented certain new and useful Improvements in Slab Shingles, of which the following is a full, clear, and exact description, reference being had to the accompanying drawing, forming part of this specification.

My invention relates to shingle structure for roofs in which a composition piece is used, which is longer than the width of a normal sized shingle, and which is so cut as to represent a number of shingles laid side by side in a course.

The usual style of composition slab or strip shingle is formed of a piece of roofing having one unbroken edge and one edge cut with deep notches, which when the strips are set in courses on a roof will give the effect of a series of rectangular shingles in courses, the notches appearing as the intervening space between individual shingles.

The main objection to the use of shingle strips of this character, and indeed to all composition or prepared roofings, is that they present a flat, unshaded appearance on the roof. It is sought to get away from this appearance by means of printing on the strips, or by special overlapping and interlocking designs.

Another defect in a good deal of prepared roofings, is that when made of light felts without excessive saturation and coating, so that they can be sold for a low price, they will curl, after exposure to the weather, or will blow up, due to their flexible nature.

It is the object of my invention to provide a strip shingle which is of fairly light material, but which is so arranged and reinforced that it cannot curl. It is also my object to provide for a greater thickness of the shingle strip at the exposed portion or butt, than at the underlying or lapped portion, thereby giving a prominence to the exposed edges of the shingle simulating tabs thereof.

More particularly, it is my object to form a strip shingle to imitate individual shingles, in which the body is bent under and is slotted through the double thickness so formed, with the slot terminating short of the edge of the doubled under portion. This gives prominence to the effect of the roofing, as will be noted, provides a dam

against water leakage, provides a strong butt and also provides a line of fold into which may be run a metal tape, wire or the like for re-inforcing and edge thickening purposes.

I am aware that others have bent under the edges of the tabs in roofing of the same general character as mine, but in all cases with which I am familiar, the turned under portion is very slight and does not extend to the full depth of the tab forming notches, and thus fails to supply the advantages which I gain with my invention.

I accomplish the various objects of my invention by that certain construction and arrangement of parts to be hereinafter more specifically pointed out and claimed.

In the drawings:

Figure 1 is a perspective view of a roof showing my device applied thereto.

Figure 2 is a detail plan of a piece of saturated felt roofing, showing lines of fold thereon.

Figure 3 is a like view showing the metal bands inserted and the folds turned under.

Figure 4 is a like view showing the notches cut out at one side of the double piece shown in Figure 3, this view being on a larger scale.

Figure 5 is a lengthwise section taken through one of the strips, as shown in Figure 4.

Figure 6 is a diagrammatic section taken through a roof showing three of the strips, as laid, with the center one sectioned and the two others plain for purposes of clearness. This view shows curves in the strips which will not be present due to their stiffness, but seemed the easiest and clearest way to bring out the point.

In the manufacture of my devices I preferably proceed in the following manner:

A double width strip of felt roofing 1 is suitably treated and is then scored along the sides with lines 2, 2, to define a line of fold (Fig. 2). The strip passes along in the roofing machine, and has superimposed along the lines of fold on both sides a strip of metal 3, which may be a wire or a true strip, as desired. The roofing strip then passes through a folder, in which suitable deflectors and then a pair of rolls cause the edges 4 of the strip to be folded under. This operation which will preferably be done while the saturating material is still hot in the felt piece, will result in the turned un-

der fold being cemented to the body of the piece.

After this operation the piece is passed through a slotter, which cuts a series of transverse, interspaced, closed end slots or notches 5 into the felt at the edges of the piece. A slitter then cuts the piece down the middle along the line 6, and a chopper cuts the individual pieces into sections suitable for flat shipment, along lines 7.

The resulting piece (Fig. 4) has a body portion 8, and tabs or projections 9, interspaced by notches 5. The metal strip is cut away in the above operation, and is left in the line of fold of each tab. The notches are not cut in deeply enough to penetrate the inner edge of the folded under piece, so that the tabs are of double thickness, and the back ends of the notches are protected by the dam formed by the intact inner edge of the underfold.

As dimensions for a strip of the above character, I give the following, which it will be understood are illustrative of one form only of the invention, but of a form which I have found desirable.

I find that the ultimate pieces may be 32 inches long, slots or notches one half inch on each end of the piece, and one inch across between the tabs. The slots will be five inches deep, and the underfold six inches deep. The tabs will be nine and two thirds inches across.

The above specifications will serve for a three tab strip, and for a four tab or two tab will follow except for overall length of the piece.

I have not attempted to describe methods of making odd shapes, such as half hexagon tabs or chamfered edge tabs, as the process will be about the same excepting for the shape of the cutouts, or notches.

If a wide piece of felt is to be used it may be first slit lengthwise into double width sections and then passed through the forming and cutting process above detailed.

In laying the strip of the dimensions above set forth (Fig. 6) the result will be that the strips when laid on the roof so that the free edges of the tabs of one course, come to a line even with the inner ends of the notches of the preceding course, will give a very shadowed appearance. I have by letters indicated the points of thickness of coverage for a typical strip. Thus at A there will be five thicknesses, at B four, at C three, at D two, and at E one thickness between the top of each strip and the roofing boards F.

One advantage of my roof is thus that each slab considered transversely of its length is of a wedge shape tapering from one thickness of felt, to five thicknesses at the exposed, shadow throwing edge, and the walls of the notches, are of two thicknesses,

throughout, including the inner walls of closed ends of the slots.

Thus the effect on the roof is even more striking than is obtained by the most expensive, taper cut slates, and wooden shingles, and in addition the piece has flexibility, is made out of inexpensive material, and can be shipped without danger of breakage.

In nailing down my strip the nail will be inserted just behind each slot, as indicated at G in Fig. 1, this nail passing through the underfold, and also the top of the shingle. The effect of this is to hold the underpiece fast to the roof, and if expansion or contraction takes place the underpiece will hold the top piece flat down on the roof, counteracting the effect of turning up during contraction and turning down during expansion. The chief cause of curling of composition shingles of the type dealt with herein, is that the coating and saturating material dries out in part, thereby causing shrinkage. When the underfold shrinks as well as the top of the shingle, this will hold down the free edge of the tab that shrinks.

The metal strip in the end of the shingle tabs acts to prevent lateral curling, to reinforce the edge of the tab, to give an extra thickness and rounded appearance at the edge, and also to permit the tabs to be bent into a permanent curve around cupolas, as indicated in Figure 1, in the roof section H.

Due to the fact that my shingle can be made of a light weight felt, it will not be much more expensive than strip shingles which do not give anywhere near the striking and satisfactory appearance on the roof.

Each nail in the roof will hold down the double thickness of the strip in which it is placed, and also one thickness of the strip beneath it. This makes for great security against tearing out of the nails, and gives a firm mounting for each piece.

Thus while my strip gives a true wedge shape, which is not possible in strips in which only an inch or so is turned under, it also has much greater strength, and is very strong at the exposed edge. In fire risk, also my strip has great advantages. The folded edges which are exposed are fully treated with such coatings as are used, and the raw felt is not exposed at these edges at all.

Having thus described my invention, what I claim as new and desire to secure by Letters Patent is:—

1. As an article of manufacture, a strip shingle comprising an integral piece of prepared roofing material folded intermediate the longitudinal edges thereof to provide a double thickness of material, said double thickness of material having slots extending from the folded edge at right angles thereto to form a series of spaced rectangular tabs of double thickness, said strip

- hingle having a relatively wide continuous piece of a single thickness joining the upper portions of said tabs, and a relatively narrow continuous piece joining the under portions of said tabs and lying above the inner ends of the slots whereby said continuous narrow piece is disposed so as to receive the nails in the laying of the strip shingle, and to maintain the lower portions of the tabs in register with and in proper spaced relation to the upper tabs, said under portion of said strip shingle being of considerably less length than the upper or main portion thereof and terminating a short distance above the ends of said slots, whereby when said strip shingles are laid with the lower folded edges of the tabs at the upper ends of the slots in the strip below, the exposed portions of the tabs will be of greater thickness than the underlying portion lapped by the next 20 succeeding strip shingle, thereby giving prominence to the exposed edges of the tabs.
2. A strip shingle formed with a continuous body portion and a series of inter-spaced tabs along one side thereof, with the material of the shingle folded under at the tab portions thereof to form a double thickness tab through the length of the tab, and a metal piece inserted across the line of fold at the end of the tab.
